US00D503973S

(12) United States Design Patent (10) Patent No.: **US D503,973 S**
Millan (45) Date of Patent: **** Apr. 12, 2005**

(54) ACTIVE SUBSTANCES DIFFUSER

D487,144 S * 2/2004 Choke-arpornchai et al. ... D23/366

(75) Inventor: **Jordi Basagañas Millan**, Barcelona (ES)

* cited by examiner

(73) Assignee: **DBK España, S.A.**, Barcelona (ES)

Primary Examiner—Lisa Lichtenstein
(74) Attorney, Agent, or Firm—Michael Best & Friedrich LLP

(**) Term: **14 Years**

(57) CLAIM

(21) Appl. No.: **29/187,628**

The ornamental design for an active substances diffuser, as shown.

(22) Filed: **Aug. 5, 2003**

DESCRIPTION

(30) **Foreign Application Priority Data**

Feb. 18, 2003 (ES) 156265

(51) LOC (7) Cl. **23-04**

(52) U.S. Cl. **D23/366**

(58) Field of Search D23/366-369;

239/52, 53, 57-59, 34, 60; 261/DIG. 65;
422/305, 120; 454/157, 156

(56) **References Cited**

FIG. 1 is a first perspective view of the instant invention;
FIG. 2 is a second perspective view thereof;
FIG. 3 is a front elevational view thereof;
FIG. 4 is a right side elevational view thereof;
FIG. 5 is a bottom plan view thereof;
FIG. 6 is a rear elevational view thereof;
FIG. 7 is a left side elevational view thereof; and,
FIG. 8 is a top plan view thereof.
